UNITED STATES PATENT OFFICE.

CURTIS THORNTON, OF VERSAILLES, INDIANA.

MAIL BOX.

Application filed April 5, 1924. Serial No. 704,474.

To all whom it may concern:

Be it known that I, CURTIS THORNTON, a citizen of the United States, residing at Versailles, in the county of Ripley and State 5 of Indiana, have invented new and useful Improvements in Mail Boxes, of which the following is a specification.

This invention relates to rural mail boxes, and more particularly to a supporting means 10 therefore, which allows the box to be set back an appreciable distance off the roadway, in which position it is entirely out of the way of the traffic, and which means allows the box to be moved in the direction of 15 the roadway by the carrier when he desires to have access to the box.

More specifically stated, the invention contemplates the provision of a mail box support which includes a sectional post, one section 20 being stationary, while the other section which supports the box is mounted for both pivotal and sliding movements with relation to the fixed section, so that the movable section can be arranged normally in a 25 vertical position, and conveniently swung to a horizontal position, and subsequently moved in the direction of the roadway by the carrier in order to permit access being had to the box without leaving the vehicle 30 in which he is travelling.

The nature and advantages of the invention will be better understood when the following detailed description is read in connection with the accompanying drawings, 35 the invention residing in the construction, combination and arrangement of parts as claimed.

In the drawings forming part of this application, like numerals of reference indicate similar parts in the several views, 40 and wherein:

Figure 1 is a view in elevation showing the normal position of the movable section of the post.

Figure 2 is a view showing the initial position occupied by the movable section of the post when swung upon its pivot.

Figure 3 is a view showing the final position of the movable section when the box is 50 moved toward the roadway for the purpose above stated.

Figure 4 is a perspective view of the movable section of the post and box.

Figure 5 is a perspective view of the 55 movable post section.

Figure 6 is a fragmentary view taken at a right angle to Figure 1.

Figure 7 is a sectional view taken on line 7-7 of Figure 4.

Referring to the drawings in detail, 10 60 represents a stationary post section, while 11 indicates a movable post section which is mounted for both pivotal and sliding movements with relation to the fixed section 10 in a manner and for a purpose to be herein- 65 after described. It might here be stated, that the respective sections of the post can be constructed from any suitable material and also vary in size and shape without departing from the spirit of the invention. 70

Rising from the opposed sides of the fixed section 10 are curved arms 12, these arms being arranged in pairs and spaced a sufficient distance apart to allow the movable section 11 pivotal movement between said 75 arms. The free ends of these arms terminate in a plane with the longitudinal center of the section 10, and support a transverse bolt 13. The outer edge of each arm is also formed with a series of teeth 14 which co- 80 operate with an element carried by the section 11 to support the latter in its normal position.

The movable section 11 supports a mail box 15 at the upper end thereof, and this 85 mail box may be of any configuration formed and provided with a gravity control door 16, which automatically closes when the movable section 11 is arranged in a vertical position, and automatically opens when said 90 section is swung to a horizontal position. Carried by this movable section 11 and ar- 95 ranged longitudinally thereof are spaced loop like members 17 which receive the bolt 13 associated with the curved arms 12 which arrangement associates the movable section 11 with the fixed section 10 of the post and at the same time allows the movable section to be swung from a vertical to a horizontal 100 position, and subsequently slide in a horizontal plane toward or away from the fixed section 10. A yoke 18 is carried by the movable section 11 and is arranged to en- 105 gage the teeth 14 of the curved arms 12 as shown in Figure 1 to support the movable section upon the fixed section 10. The arms 12 are provided with attaching ears 19 hav- 110 ing a plurality of openings 20, so that the arms can be adjusted vertically on the fixed section 10 to vary the height of the box 110

as will be readily understood. The yoke 18 is preferably formed with an eye 21 to permit of the use of a rod 22 for the purpose of swinging the section 11 to a horizontal 5 position, and subsequently reciprocate the body in a horizontal plane. This rod is formed with a hook terminal 23 adapted to be received by the eye 21 of the yoke, and is used by the carrier, so that the box can 10 be manipulated in the manner stated without the driver leaving the vehicle or the like in which he is travelling.

In practice, the parts are normally arranged in the manner shown in Figure 1, 15 which arrangement of the parts allows the box in its entirety to be arranged an appreciable distance off the roadway out of the way of traffic. When the carrier approaches the box, he makes use of the rod 22, which 20 is extended to engage the eye 21 of the yoke 18, and by pulling on this yoke, the box is tilted from a vertical to a horizontal position upon the bolt 13, which is arranged within the loop like members 17, so that the 25 carrier can draw the movable section toward the roadway and thus bring the box 15 within his reach. As above stated, the door 16 of this box is weighted to automatically open when the movable section 11 is arranged horizontally, so that the carrier can 30 have ready access for the purpose of collecting or depositing mail matter. The box is returned to its normal position by simply reversing the movements just stated, and as 35 the box is swung to a vertical position, the yoke engages the teeth 14 on the curved arms and supports it in this position.

While it is believed that from the forego-

ing description, the nature and advantages of the invention will be readily apparent, 40 I desire to have it understood that I do not limit myself to what is herein shown and described, and that such changes may be resorted to when desired as fall within the scope of what is claimed. 45

Having thus described the invention, I claim:

1. In combination, a post including a stationary section, curved arms rising above said section, a movable section mounted on said arms for both pivotal and sliding movements, a mail box carried by one end of the movable section, teeth formed on said curved arms and a yoke carried by the movable section and adapted to engage said teeth to normally support said section in parallelism with the fixed section. 50

2. In combination, a post including a stationary section, curved arms rising therefrom and having aligned openings, a movable section adapted to operate between the spaced arms, and including spaced parallel slotted members, a bolt adapted to be passed through the corresponding openings in said arms and through the slots of said parallel members to support the movable section for pivotal movement, and also for sliding movements in both horizontal and vertical planes, cooperating means carried by the movable section and said curved arms for 60 supporting the former in a vertical position, and a box carried by the other end of the movable section. 65

In testimony whereof I affix my signature.

CURTIS THORNTON.
